UNITED STATES PATENT OFFICE.

ELMORE EDWARD SABIN, OF EAST OAKLAND, CALIFORNIA.

GLOVE.

No. 923,374.

Specification of Letters Patent.

Patented June 1, 1909.

Application filed March 11, 1909. Serial No. 482,716.

To all whom it may concern:

Be it known that I, ELMORE EDWARD SABIN, a citizen of the United States, residing at East Oakland, in the county of Alameda and State of California, have invented 5 certain new and useful Improvements in Gloves; and I do declare the following to be a full, clear, and exact description of the invention, such as will enable others skilled in the art to which it appertains to make and use the same.

This invention relates to improvements in gloves and more particularly in that class of gloves which are made from leather or other 15 suitable material cut and sewed in form.

The object of the invention is to provide a glove of this general character of simple and improved construction in which a minimum 20 number of pieces is required whereby economy is effected in the cutting and sewing of the glove and a novel and improved arrangement of seams is afforded giving rise to increased strength and durability.

The invention consists of certain novel 25 features of construction and arrangement of parts of the improved glove whereby certain important advantages are attained and the glove is made simpler, cheaper, and otherwise adapted for convenient use as will be 30 hereinafter fully set forth.

In the accompanying drawings Figure 1 is 35 a plan view of the cut out blank from which the main or body portion of the glove is formed. Fig. 2 is a similar view of the 40 smaller or auxiliary part of the glove. Fig. 3 is a plan view of the back of the glove showing the location of certain seams, Fig. 4 is a similar view of the palm showing the location of the seams forming the thumb as viewed from the palm with the thumb turned down.

In the embodiment illustrated is shown a 45 glove composed of two parts, a main or body portion 1 and a smaller auxiliary finger portion 2, the outline of these parts being clearly illustrated in Figs. 1 and 2.

The main or body portion 1 of the glove 50 comprises in integral form all of the fourchettes or finger members for the improved glove with the exception of the outer or back member for the third or ring finger which latter member is formed from the auxiliary portion 2 which in the course of manufacture

is joined to the body portion 1 as will be 55 hereinafter fully described.

The main or body portion 1 is to be centrally and transversely folded as indicated by the dotted line 3 in Fig. 1 to produce the palm or back portions or plies 5 and 6, the line of folding extending centrally along of 60 the fourth or little finger 4, one member of which is thus carried upon each of the said palm and back portions or plies 5 and 6 of the glove.

Upon the palm portion 6 of this improved 65 glove are integrally formed the inner or palm members of the fourchettes 7, 8, 9, and 10, of the first, second, third and fourth fingers respectively, and the inner and outer fourchettes 11 and 12 of the thumb; the finger 70 members being arranged adjacent to each other and projecting from the same edge of the body portion 1. The back or outer fourchette 7^a for the first or index finger also projects from the same edge of the body portion 75 1 and is integrally connected with the inner or palm member of the aforesaid finger and is adapted to be folded over on the dotted line 7^b (see Fig. 1) to bring it into position on the back or outer face of the glove. The lower 80 edge of the fourchette 7^a is provided with a depending tongue 7^c designed to be stitched to the transversely extending edge arranged at the base of the outer half of the middle 85 finger member to be described. Formed integrally with the outer or back ply 5 are the outer or back fourchettes 13, 14, of the fourth and second or middle fingers, the fourth 90 finger fourchette 13 being integral with the inner fourchette 10 of said little finger and is foldable on the dotted line 3 as above described the free edges being designed to be stitched together. Between the members 13 and 14 is a space 15 having its lower edge 16 curved upwardly as shown in Fig. 1 and to 95 which the lower edge of the outer fourchette of the third or ring finger formed by the auxiliary member 2 is stitched when the parts are assembled said part 2 being provided with tongues 2^a and 2^b and the cut out portions 2^c 100 and 2^d arranged adjacent said tongues and designed to be connected with the inclined edge 14^a of the middle finger member 14 and with the edge 13^a of the little finger member 13 to provide a properly shaped finger. This 105 extra member 2 is stitched along its side

edges to the corresponding edges of the inner fourchette 9 of the ring finger.

An upwardly inclined edge 7^a is formed at the base of the fourchette 7^a extending from 5 the free edge thereof to the base of the tongue 7^c and is adapted to be connected with the inclined edge 14^b at the base of the back portion 14 of the second finger. The curved cut out edge 7^e is designed to fit and be stitched 10 to the curved edge 5^a formed on the back ply 5 opposite the edge 14^b at the base of the fourchette 14.

The thumb is cut as is shown in Fig. 1 and comprises the inner or palm fourchette 11 having one side made integral with the outer fourchette 12 thereof said fourchette 11 being disconnected at its base from the palm ply thus leaving an edge 17 to which the upper portion of the side 11^a of the flap or gore 20 15 made integrally with the fourchette 12 is designed to be connected, preferably by stitching. The other edge 21 of this gore 20 is connected with the lower free edge 11^a of the fourchette 11 of the lower outer curved edge 25 22 and is stitched to the curved edge 7^b at the base of the fourchette 7. The inner straight edge 23 of the gore 20 is stitched to the edge 5^b at the free edge of the back ply 5 and the curved edge 5^c of said ply is stitched to the 30 edge 5^a formed opposite the edge 23 on the gore 20. The several palm and back fourchettes for the first second third and fourth fingers are stitched together along their side and top edges in the ordinary way, the auxiliary portion 2 being stitched to the back ply 35 as above described.

By this arrangement it will be evident that upon the palm portion or ply 6 are formed the palm members or fourchettes for each of 40 the several fingers and the thumb of the glove also the back or outer fourchette for the thumb and for the first finger while upon the outer or back ply 5 there are produced only the members 13 and 14 for the alternate 45 finger portions of the glove, that is of the fourth and second fingers. The intervening space 15 between these alternating fingers or portions being designed to receive the auxiliary member 2 which forms the back portion 50 or fourchette for the third or ring finger.

In joining the two members to produce the glove the several palm and back fourchettes for the fourth, second and first fingers are sewed in the ordinary way, the auxiliary portion 2 being stitched along the edge 16 to produce a seam extending across the knuckle of the third finger as is shown in Fig. 3.

From the foregoing description taken in connection with the accompanying drawings, 60 the construction and operation of the invention will be readily understood without requiring a more extended explanation.

Various changes in the form, proportion and minor details of construction may be

resorted to without departing from the principle or sacrificing any of the advantages of this invention as defined in the appended claims.

What I claim as my invention is:

1. A glove comprising a palm ply or portion having integral palm fourchettes for the fingers, the back and palm fourchettes for the thumb, the fourchettes for the fingers being side by side and that for the first or index finger comprising palm and outer members 75 integrally connected along one side and the palm thumb fourchette being cut out at the base of the first finger fourchettes, and the back thumb fourchette being integral with said palm fourchette and arranged at the 80 edge of said palm portion opposite to the first finger fourchette, a back ply having integrally connected outer fourchettes for the second and fourth fingers separated by a space adapted to receive the outer member 85 of the third finger fourchette, said outer member for the first finger portion being stitched to the back ply by a seam extending across the knuckle of the first finger to the thumb portion of the glove. 90

2. A glove comprising integral palm and back portions or plies foldable transversely, the palm member having integrally formed at one edge the palm fourchettes for the first second, third and fourth fingers and the 95 back fourchette for the first finger, palm and back fourchettes for the thumb formed integral with said palm member, the base of said thumb palm fourchette being separated from the palm member or portion of the glove, a 100 gore or flap extending laterally from the palm member at the base of the back fourchette for the thumb, the back glove member having extending from one edge thereof integral back fourchettes for the middle and 105 second fingers with a space arranged between them to receive a detachable back fourchette for the third finger and a cut out portion formed at the base of said middle finger and extending to the outer edge thereof. 110

3. A glove comprising integral palm and back portions or plies foldable transversely, the palm member having integrally formed at one edge the palm fourchettes for the first, second, third, and fourth, fingers and the 115 back fourchette for the first finger, palm and back fourchettes for the thumb formed integral with said palm member, the base of said thumb palm fourchette being separated from the palm member or portion of the glove, a 120 gore or flap extending laterally from the palm member at the base of the back fourchette for the thumb, the back glove member having extending from one edge thereof integral back fourchettes for the middle and 125 second fingers with a space arranged between them to receive a detachable back fourchette for the third finger and a cut out

portion formed at the base of said middle finger and extending to the outer edge thereof, and a tongue formed at the base of the back fourchette of the first finger and
5 adapted to be connected with the edges of the cut out portion at the base of the back fourchette of the middle finger.

In testimony whereof I have hereunto set my hand in presence of two subscribing witnesses.

ELMORE EDWARD SABIN.
